GASEOUS DISCHARGE DEVICE

Paul W. Stutsman, Needham, Mass., assignor to
 Raytheon Manufacturing Company, Newton,
 Mass., a corporation of Delaware

Application February 3, 1951, Serial No. 209,220

10 Claims. (Cl. 313—187)

1

This invention relates to gaseous-electron-discharge devices containing electrodes comprising wires of extremely small diameter.

This invention discloses the discovery that, when an electrode comprising an extremely fine wire having a diameter on the order of .001 of an inch is positioned adjacent a source of electrons, such as an indirectly-heated cathode in a gaseous medium, and a positive voltage is applied to said electrode with respect to said electron source, electrons attracted from the source toward the electrodes will collide with gas molecules producing ions and electrons greatly in excess of that required to maintain a discharge between the electron source and the fine wire electrode.

As a result, if an anode having a substantial surface is placed in the vicinity of the discharge between the electron source and the fine wire electrode, for example, by making the anode in the form of a cylinder surrounding both the electron source and the fine wire electrode, a substantial quantity of electrons will flow from the electron source to the anode even with no potential difference between the anode and the electron source.

Indeed, it has been found that substantial quantities of electrons will flow from the electron source to the anode when the anode is negative with respect to the electron source, the magnitude of this electron flow being a function of the positive voltage applied to the thin wire electrode and the amount of the negative voltage applied to the anode. Because of this phenomenon, it is possible to use a gaseous-electron-discharge device of this type as a voltage-transforming device, wherein relatively high voltage at low current may be converted to low voltage at relatively high current.

It has further been discovered that, if a particular potential is applied between the thin wire electrode and the electron source, and a positive potential is applied to the anode, the drop between the anode and the electron source will remain substantially constant over a relatively wide range of anode currents, thus demonstrating that the device has the characteristics which will enable it to operate as a gaseous-voltage-regulating tube, and having the advantage that the desired regulating voltage may be adjusted by adjusting the potential applied to the thin wire electrode, and also that the regulated voltage developed between the cathode and anode of the device will be considerably below the operating voltages obtainable by other types of gaseous-

2

tube regulators. For example, the regulated voltage may be on the order of ten volts or less.

Further, since the voltage developed between the cathode and anode may be varied as a function of the thin wire electrode voltage, the device exhibits the properties of an amplifier, and may be so used, if desired.

It has been discovered that a particularly useful gaseous medium for this discharge device comprises a mixture containing substantially ninety per cent krypton and ten per cent xenon at a total pressure of one hundred microns of mercury.

Other and further objects and advantages of this invention will be apparent as the description thereof progresses, reference being had to the accompanying drawing, wherein:

Fig. 1 illustrates a longitudinal, cross-sectional view of a gaseous-electron-discharge device embodying this invention, taken along line 1—1 of Fig. 2;

Fig. 2 illustrates a transverse, cross-sectional view of the device shown in Fig. 1, taken along line 2—2 of Fig. 1; and

Fig. 3 illustrates a graph showing operational characteristics of the device illustrated in Figs. 1 and 2.

Referring now to Figs. 1 and 2, there is shown an envelope 10 which may be, for example, of glass, said envelope being sealed to a glass press 11 at the bottom thereof. Extending upwardly from the glass press 11 is a plurality of supports which are attached to various elements of the discharge device. A support 12 is attached to a cathode 13 which is shown here as a cylinder coated with electron-emissive material 14, and heated by a heater wire 16 connected to the support and lead-ins 17 and 18, respectively, said lead-in members extending through the glass press 11 to provide electrical contacts external to the envelope 10.

Surrounding cathode 13 and spaced therefrom is an anode cylinder 19 which is coaxial with the cathode 13. Cylinder 19 is supported by a pair of side rods 20 and 21, respectively, whose lower ends are imbedded in the glass press 11. Upper and lower mica spacers 22 and 23, respectively, cover the ends of anode cylinder 19 and extend slightly over the ends of the cathode cylinder 13, said mica spacers extending substantially out to the walls of envelope 10. Rods 20 and 21 extend through mica spacers 22 and 23, thereby insuring that the anode cylinder 19 remains accurately positioned with respect to the cathode 13.

An auxiliary electrode comprising a thin wire

24 extends between the mica spacers 22 and 23 parallel to the cathode cylinder 13 at a point approximately a half wave between the cathode cylinder 13 and the anode cylinder 19. At its lower end wire electrode 24 is attached to a lead-in support 25, and at its upper end wire electrode 24 is attached to a spring support 26 which, in turn, is attached, as by welding, to a rod 27, one end of which is imbedded in glass press 11, and extends upward through the mica spacers 22 and 23 outside the anode cylinder 19.

Referring now to Fig. 3, there is shown a graph illustrating the operation of the gaseous-discharge device of Figs. 1 and 2. Along the axis of ordinates is plotted anode voltage relative to the cathode 13, while along the axis of abscissas is plotted anode current in milliamperes. Curve 28 illustrates the characteristic of the device which would allow its use as a step-down voltage transformer. As is shown by point 29, at zero current, the anode voltage is minus between one and two volts when one hundred and ten volts are applied between the auxiliary wire electrode and the cathode, said auxiliary wire electrode voltage being labeled *eg* on the graph of Fig. 3. With *eg* remaining constant at one hundred and ten volts, the anode voltage becomes less negative as the anode current increases from zero until, at approximately thirty milliamperes of current, the anode voltage is approximately zero, as is indicated by point 30. Thus, if one hundred and ten volts are applied to the auxiliary electrode, and a current of around fifteen milliamperes is allowed to flow in the anode-cathode circuit, a negative voltage on the order of one volt will appear between the anode and the cathode, said voltage being available, for example, for biasing other electron-discharge tubes or for supplying a heater current to other electron-discharge tubes.

As is shown in this graph by way of example, with the auxiliary electrode held constant, for example, at one hundred and ten volts, the plate voltage rises rapidly between currents of forty and fifty milliamperes of plate current until the anode voltage reaches a voltage on the order of eight or ten volts, at which time the voltage again levels off as the discharge device approaches conditions of arc discharge. If a voltage of, for example, fifty volts is applied to the auxiliary electrode, the anode-cathode voltage drop will remain substantially constant at approximately one-half a volt for a current range of from twenty to forty milliamperes, thus providing a characteristic which may be used to produce a low-voltage-regulated output across the anode-cathode circuit of the device, said anode being connected, for example, to a higher voltage source through a dropping resistor in accordance with well-known voltage regulator practice. This is illustrated by a curve 31 in Fig. 3.

If the voltage applied to the auxiliary electrode is zero, the anode-cathode voltage drop will be on the order of eight volts, while, for various voltages applied to the auxiliary electrode between zero and fifty volts, various curves having substantially constant voltages in the current range between twenty and forty milliamperes may be obtained. These curves are shown, for example, by the dotted lines 32; said curves substantially matching with curve 28 when anode currents exceed between forty and fifty milliamperes.

It should be noted that the efficiency of generation of the excess positive ions by the thin wire electrode is dependent on the diameter of the thin

wire. For optimum results, the diameter of the thin wire should be much less than the length of the mean free electron path, for example, one tenth the length thereof. In addition, the gas pressure must be sufficient to produce enough ions to substantially neutralize the electron space charge of the device. While the particular gaseous medium disclosed herein comprised krypton and xenon at a pressure of one hundred microns of mercury, other gases, such as mercury or helium, could be used, and the pressure of the gaseous medium could be as low as fifty microns of mercury. At the low pressure of fifty microns, results may be obtained with thin wire electrode diameters as high as .004 of an inch. When higher pressures are used, for example, pressures of greater than one thousand microns of mercury, the thin wire electrode diameter should be very small, for example, less than .001 of an inch.

This completes the description of the particular embodiment of the invention illustrated herein. However, many modifications thereof will be apparent to persons skilled in the art without departing from the spirit and scope of this invention. For example, the auxiliary wire electrode has a current voltage characteristic which prevents an arc from occurring between the electron source and the auxiliary electrode. This portion of the tube could be used alone as a resistance having a positive voltage current characteristic throughout its entire range of applied voltages. In addition, the particular configuration of the electrodes and their support means is by way of illustration only. Accordingly, it is desired that this invention be not limited by the particular details of the embodiment described herein, except as defined by the appended claims.

What is claimed is:

1. A gaseous-electron-discharge device comprising an envelope containing a gaseous medium, a source of electrons, an anode, and an auxiliary electrode, said electrode comprising a wire having a diameter on the order of .001 of an inch.
2. A gaseous-electron-discharge device comprising an envelope containing a gaseous medium, a source of free electrons, and an electrode spaced from said source, said electrode comprising a wire having a diameter on the order of .001 of an inch.
3. A gaseous-electron-discharge device comprising an envelope containing a gaseous medium, a cathode of the heated type, and an electrode spaced from said cathode, said electrode comprising a wire having a diameter on the order of .001 of an inch.
4. A gaseous-electron-discharge device comprising an envelope containing a gaseous medium, a cathode, an anode, and an auxiliary electrode, said electrode comprising a wire having a diameter on the order of .001 of an inch.
5. A gaseous-electron-discharge device comprising an envelope containing a gaseous medium, an indirectly heated cathode, an anode, and an auxiliary electrode, said electrode comprising a wire having a diameter on the order of .001 of an inch.
6. A gaseous-electron-discharge device comprising an envelope containing a gaseous medium, a cathode, an anode coaxial with said cathode, and an auxiliary electrode, said electrode comprising a wire having a diameter on the order of .001 of an inch.
7. A gaseous-electron-discharge device comprising an envelope containing a gaseous medium, a source of electrons, said medium comprising an inert gas, and an electrode spaced from said

source, said electrode comprising a wire having a diameter on the order of .001 of an inch.

8. A gaseous-electron-discharge device comprising an envelope containing a gaseous medium, a source of electrons, said medium comprising an inert gas at a pressure on the order of one hundred microns of mercury, and an electrode spaced from said source, said electrode comprising a wire having a diameter on the order of .001 of an inch.

9. A gaseous-electron-discharge device comprising an envelope containing a gaseous medium, a source of electrons, said medium comprising krypton and xenon at a pressure on the order of one hundred microns of mercury, and an electrode spaced from said source, said electrode comprising a wire having a diameter on the order of .001 of an inch.

10. A gaseous-electron-discharge device, an envelope containing a gaseous medium at a pressure on the order of one hundred microns of mercury, a source of electrons, and an electrode spaced from said source, said electrode having a diameter substantially less than the mean free electron path in said medium.

PAUL W. STUTSMAN.
